UNITED STATES PATENT OFFICE.

RICHARD H. HOYT, OF BUFFALO, NEW YORK.

WASHING-MACHINE.

1,046,788.

Specification of Letters Patent. Patented Dec. 10, 1912.

Application filed May 9, 1912. Serial No. 696,088.

To all whom it may concern:

Be it known that I, RICHARD H. HOYT, a citizen of the United States, residing at Buffalo, in the county of Erie and State of New York, have invented new and useful Improvements in Washing-Machines, of which the following is a specification.

This invention relates to a clothes washing machine of that type which comprises a hollow drum adapted to receive the clothes to be washed and having openings in its periphery whereby water is admitted to and discharged from the drum upon oscillating the same within a housing or tank containing the wash water.

It is the object of this invention to so construct the drum that water from the tank is circulated more rapidly through the drum upon oscillating the latter, thereby not only rendering it possible to perform the washing operation with less water, but also effecting a saving in the use of soap, bleach and bluing and permitting the clothes to lie closer to the rubbing bars on the inner side of the cylinder and subjecting them to a more thorough rubbing or cleaning action than is possible when an excessive amount of water is used which tends to float the clothes away from the rubbing bars.

Furthermore, my improved washing machine is not liable to pull or cut the buttons off the clothes while washing the same and the operator is also not liable to be injured when placing the washing compounds within the drum when this is done while the machine is in operation.

In the accompanying drawings consisting of 2 sheets: Figure 1 is a vertical longitudinal section of a washing machine embodying my improvements but showing the drum from the exterior thereof. Fig. 2 is a vertical cross section in line 2—2, Fig. 1. Fig. 3 is a vertical longitudinal section taken in line 3—3, Fig. 2. Fig. 4 is a side elevation, on an enlarged scale, of one of the bucket slats or staves of the drum. Fig. 5 is a top plan view thereof. Fig. 6 is a transverse section, on an enlarged scale, taken in line 6—6, Fig. 5.

Similar characters of reference indicate corresponding parts throughout the several views.

In its general organization the washing

machine embodying my improvements comprises an outer casing, shell or tank 1 which is adapted to hold a charge of water and which is preferably constructed of wood in the form of a cylinder having its axis arranged horizontally and provided in its top with an opening through which access may be had to the interior of the tank. The opening in the top of the tank is normally closed by a cover 2 which is preferably slidably circumferentially on the outer side of the tank.

Within the tank is arranged a washing drum of cylindrical form having its axis arranged horizontally and preferably in line with the axis of the tank. This drum preferably comprises a cylindrical wall or body 3 of wood, and wooden heads 4 arranged at opposite ends of the body and provided with axial trunnions 5 journaled in bearings 6 in the adjacent heads of the tank. The drum is turned alternately in opposite directions this being accomplished by any of the suitable and well known means now in common use in this type of machine.

The body of the drum is built up of a plurality of staves or slats 7, 8, 9 which are all constructed of wood inasmuch as this material is best adapted for washing clothes without injuring the same. Each of the staves 7 is constructed to project inwardly from the inner side of the drum so as to form an internal rubbing bar or beater 10 which is adapted to engage with the clothes and clean the same by rubbing and tumbling them around within the drum in the well known method practiced in machines of this character.

The staves 8 are provided with means whereby the water can flow from the tank into the drum and vice versa during the washing operation, and are hereinafter referred to as bucket staves. The staves 9 are plain and not provided with water conduits nor do they project inwardly from the wall of the drum. The main part of the body of the drum is constructed of rubbing bar staves and bucket staves which may be distributed in any suitable order but preferably by arranging a rubbing bar stave in alternation with every two bucket staves. One part of the body of the drum is mov-

- able laterally and forms a door which normally covers an opening in the drum through which the clothes may be introduced into the drum and removed therefrom.
- 5 This door is preferably made up of two plain staves 9, 9 arranged at its opposite longitudinal edges, a central rubbing bar stave 7, and two bucket staves 8 arranged between opposite sides of the last mentioned 10 rubbing bar staves and the plain staves.
- 10 This door is preferably connected at one of its longitudinal edges by means of hinges 11 to one of the longitudinal edges of the relatively fixed part of the body of the drum.
- 15 and is held in its closed position by means of two catches 12 mounted on the free edge of the door and adapted to engage with the adjacent part of the body of the drum, as shown in Figs. 1 and 2.
- 20 Each of the bucket staves is provided on its outer side with a longitudinal rib 13 which is arranged midway between opposite longitudinal edges of this stave and forms longitudinal rabbets 14 at both of the outer 25 longitudinal corners of this stave, as shown in Figs. 2 and 6. Each of these bucket staves is provided with two rows of water passages each of which extends from the inner corner of one of its rabbets on the outer 30 side thereof inwardly to the inner side of this stave, this passage comprising an intermediate portion 15 which is inclined or arranged at an angle to a line drawn to the radius of the drum, an inner portion 16 extending inwardly from the inner end of the 35 inclined portion and arranged parallel with the radial line of the drum, and an outer portion 17 flared outwardly from the outer end of the inclined portion to the inner corner of the respective rabbet. The water 40 passages of each row extend from one rabbet of the bucket stave inwardly and in a direction opposite to the other row of water passages of this stave which extends inwardly from the other rabbet thereof so that 45 these two rows of water passages cross each other. In the preferred construction of these bucket staves the water passages of one row thereof alternate with the water 50 passages of the other row, thereby permitting a comparatively large number of these passages to be formed in each stave and the outer ends of the same to be flared to a considerable extent and permit the maximum 55 amount of water to be admitted into these passages upon turning the drum within the water of the tank.

As the drum turns in one direction the water in the tank is caught by the advancing 60 rabbets of the several bucket staves and received by the flaring outer ends of the water passages which open into these rabbets and is conveyed by these passages to the interior of the drum where it is delivered 65 against the clothes therein. As the drum

turns in the opposite direction the other rabbets of the bucket staves operate to catch the water in the tank and direct the same into the flaring outer ends of the other water passages which conduct the water in like 70 manner to the interior of the drum and upon the clothes therein. While the water is being thus delivered into the drum by those water passages which are advancing with their inlet ends a corresponding amount of 75 water is discharged from the drum through those water passages which for the time being have their outer ends trailing relatively to the direction of movement of the drum. By this means a comparatively rapid circulation of water is produced from the tank 80 into the drum and then back again to the tank.

The employment of less water for washing purposes effects a considerable saving 85 inasmuch as less fuel is required for supplying heated water, less washing compound is necessary for treating the water, such as soap, bleach and bluing and washing of each batch of clothes is also expedited inasmuch 90 as the time required for filling the tank with clean water and emptying the same of its soiled water is materially reduced.

By flaring the outer ends of the water 95 passages the maximum volume of water is scooped up from the tank and forced through the water passages into the drum in the form of a plurality of jets which strike the clothes and aid the rubbing bars in loosening and removing the dirt from 100 the clothes.

By arranging the inner ends of the water 105 passages parallel with the radius of the drum the formation of sharp edges on the inner ends of these passages is avoided, thereby preventing pulling or cutting off 110 the buttons from the clothes which are being washed which would be liable to occur if sharp edges were formed on the bucket slats or staves at the inner ends of the water 110 passages by opening the latter at an angle to the radial line at the inner sides of these staves.

By employing less water in the machine 115 the clothes are permitted to lie closer to the rubbing bars and therefore receive a more thorough and quick cleaning action from these rubbing bars than when a greater amount of water is used, because the greater amount of water tends to lift the clothes to 120 the center of the drum where the rubbing bars cannot reach the same as effectively. In operating these machines the attendants usually put the cleaning compounds in the tank without stopping the movement of the 125 drum and as the present drum is practically smooth on its exterior the same is less dangerous to the operatives than a machine in which the drum is provided with a pronounced projection on its periphery. Fur- 130

thermore, this drum is very compact and has no delicate parts which are liable to become broken or deranged.

I claim as my invention:

5. 1. A washing machine comprising a water tank, a drum rotatable in said tank and having a cylindrical wall containing a plurality of longitudinal staves, each of which is provided on its outer side with a longitudinal 10 rib forming rabbets at opposite outer longitudinal corners of said stave and each stave being also provided with two rows of inclined water passages, the passages of one row extending inwardly from one of said 15 rabbets in a direction opposite to and crossing the passages of the other row.
2. A washing machine comprising a water tank, a drum rotatable in said tank and having a cylindrical wall containing a plurality 20 of longitudinal staves, each of which is provided on its outer side with a longitudinal rib forming rabbets at opposite outer longitudinal corners of said stave and each stave being also provided with two rows of water 25 passages, the passages of one row extending inwardly from one of said rabbets and crossing the passages of the other row and each passage having an outer part which is arranged at an angle to the radius of the drum and an inner part which is parallel with 30 said radius and each of said passages having an outwardly flaring outer end.

Witness my hand this 19th day of April, 1912.

RICHARD H. HOYT.
